UNITED STATES PATENT OFFICE.

WARREN C. NEWBURY, OF EAST BOSTON, MASSACHUSETTS, ASSIGNOR TO SAMUEL CABOT, INC., A CORPORATION OF MASSACHUSETTS.

CLEANSING COMPOUND.

1,415,605.

Specification of Letters Patent.

Patented May 9, 1922.

No Drawing.

Application filed March 23, 1918. Serial No. 224,371.

To all whom it may concern:

Be it known that I, WARREN C. NEWBURY, a citizen of the United States, residing at East Boston, in the county of Suffolk and 5 Commonwealth of Massachusetts, have invented a new and useful Improvement in Cleansing Compounds, of which the following is a specification.

This invention relates to cleansing fluids 10 for softening and removing gummy, tarry or oily deposits of foreign matter, and for correcting the effect of such deposits upon finished surfaces.

More specifically my invention is directed 15 to a liquid cleansing compound for use on car bodies and the like, on which deposits of earthy matter mixed with road tar or road oil have been caked so that their removal is difficult without affecting the finish of the 20 varnish. If allowed to remain, the tar or other oily deposit penetrates the varnish and soon eats its way through the underlying coats of paint, destroying the gloss or finish.

In accomplishing my present invention, I 25 form an oily solvent which for the purposes of illustration may be indicated by the following formula: By weight 55 parts of creosote or the like, about 30 parts by weight of a light lubricating oil such as white loom 30 or spindle oil, and about 10 parts of extra boiled linseed oil, and about 5 parts of oil of turpentine.

The above proportions may be varied, it

being important to maintain a preponderance of the creosote or naphtha and the light 35 petroleum oil. These elements have a very rapid and efficient action in penetrating and softening the oily or tarry binder of the dirt, and in penetrating the face of contact between the dirt and the finished surface. At 40 the same time, the other elements have a very efficient restoring effect for a polished or otherwise finished surface which has been covered by such deposit. Such modifications as are within the limits of the 45 appended claims are understood to be in accordance with my invention.

What I therefore claim and desire to secure by Letters Patent is:

1. A liquid for removing tar or road oil 50 from finished automobile bodies or the like, comprising creosote in predominating amount, a light petroleum oil and linseed oil.
2. A liquid for removing tar or road oil 55 from finished automobile bodies or the like, and comprising a creosote in predominating amount, a light petroleum oil, and linseed oil in substantially the following proportions by weight; creosote 55 parts, petroleum 60 oil 30 parts, and linseed oil 10 parts.

WARREN C. NEWBURY.
